US0D1055028S

(12) **United States Design Patent** (10) **Patent No.:** **US D1,055,028 S**
(45) **Date of Patent:** **** Dec. 24, 2024**

(54) **PAIR OF EARPHONES**

(71) Applicant: **Target Brands, Inc.**, Minneapolis, MN (US)

(72) Inventors: **Daniel C. Rose**, Minneapolis, MN (US); **Yousin B. Smith**, Flagstaff, AZ (US); **Kent D. Katterheinrich**, Shoreview, MN (US); **Tyler J. Abrahamson**, Apple Valley, MN (US); **Nathan J. Romportl**, Minneapolis, MN (US)

(73) Assignee: **Target Brands, Inc.**, Minneapolis, MN (US)

(**) Term: **15 Years**

(21) Appl. No.: **29/875,768**

(22) Filed: **May 10, 2023**

(51) **LOC (14) Cl.** **14-01**

(52) **U.S. Cl.** **USPC** **D14/223**

(57) **CLAIM**

The ornamental design for a pair of earphones as shown and described.

DESCRIPTION

FIG. 1 is a perspective view of one earphone of a pair of earphones showing our new design, the earphone of FIG. 1 is configured for use with a right ear of a user;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is a perspective view of one earphone of the pair of earphones, the earphone of FIG. 8 is configured for use with a left ear of a user;

FIG. 9 is a front view of FIG. 8;

FIG. 10 is a back view of FIG. 8;

FIG. 11 is a top view of FIG. 8;

FIG. 12 is a bottom view of FIG. 8;

FIG. 13 is a left side view of FIG. 8; and,

FIG. 14 is a right side view of FIG. 8.

The broken lines shown in the drawings are included for purposes of illustrating portions of the pair of earphones and form no part of the claimed design.

1 Claim, 8 Drawing Sheets
